FILE FASTENER

Harry D. Snyder, New York, N. Y., assignor, by
mesne assignments, to Speed Products Com-
pany, Inc., Long Island City, N. Y., a corpora-
tion of New York

Application April 18, 1944, Serial No. 531,556

3 Claims. (Cl. 24—153)

1

The invention is a file fastener wherein a compressor is removably threaded onto a pair of companion prongs of a base member for holding a stack of sheets of paper or the like in a compact and neat fashion however permitting relatively convenient removal of the several sheets of the stack by unlocking the compressor from the prongs.

The object of the invention is to provide a functionally and structurally improved compressor in the form of a cover of a length slightly less than the distance between the prongs when normal to the stack and having novel wedge means for stressing the bent down terminals of companion prongs upon rotation of the compressor along the top sheet of the stack for drawing together the compressor and base, thus more securely holding the stack in a compact fashion. The invention has as another object to provide simplified and biased means extending from the compressor for progressively clearing the bent down prongs prior to automatically interlocking the compressor and specifically a boss thereof with the bent down prongs. The invention has as a further object to provide a relatively elongated compressor having a gap surrounded completely by the body of the compressor for automatically positioning a prong in a key way whereby a transverse end of the compressor may be quickly positioned against the upper sheet of the stack of papers and against a part of the last mentioned prong whereby this prong may be readily bent over the stack upon pivotal or tiltable displacement of the compressor downwardly towards the stack. The invention has as another object the provision of a practical compressor in the form of a relatively elongated plate having a slotted portion for receiving a companion bent down prong of the strap and including a rounded wing adapted to be rotated under this companion bent down prong whereupon the sides of the compressor are readily and desirably interposed between the bent down parts of the companion prongs and the latter are automatically interlocked with the boss of the compressor. Another important object of the invention is realized in the provision of reinforcing beads for strengthening the compressor plate and at least in part characterizing wedge means for tensioning the bent over parts of the companion prongs to urge the base plate and compressor tightly towards the stack. The invention has as another salient object to provide in a one piece compressor a rim surrounding the boss thereof, the rim being interrupted by a slot extending from the outer free edge of a biased

55

2

lip and widthwise of the compressor towards and to a lower margin of the rim for threadably receiving a companion bent down prong in the matter of effectively arranging the boss to interlock with the last-mentioned prong. The invention has as further object the provision of means to permit the compressor plate to be conveniently unlocked and removed from the bent down prongs. The invention has as a further object the provision of a compressor adapted to be removably and telescopically associated with one of the bent down prongs whereby the compressor may be readily swiveled away from and towards the companion unthreaded prong for quickly threading the latter on the compressor. Other functional and structural features and advantages of the invention will appear from the following detailed specification considered in the light of the accompanying drawings wherein:

10 Fig. 1 is a perspective view of the file fastener, illustrating the compressor about to be threaded into one of the prongs of a base member or plate.

15 Fig. 2 is a perspective view showing the compressor threaded on the prong and bearing against the top sheet of the stack of papers or the like.

20 Fig. 3 is a perspective view showing the left hand prong bent down against the stack upon shifting of the compressor in the direction of the arrow shown in Fig. 2.

25 Fig. 4 is a perspective view showing the compressor threaded on one of the prongs and swung out of alignment with the companion or right hand prong of the base member and awaiting to be rotated, swiveled or pivoted towards the free but companion bent down prong.

30 Fig. 5 is a top view however illustrating the compressor pivoting in the direction of the arrow with the clearing wing slightly under the right hand prong and the biased lip slightly overlapping the latter.

35 Fig. 6 is a top view showing the compressor disengagably interlocked with the bent down foldable prongs.

40 Fig. 7 is a longitudinal sectional view on the line 7—7 of Fig. 6.

45 Fig. 8 is a transverse sectional view of the compressor on the line 8—8 of Fig. 6 illustrating the greatest divergence or bias of the clearing lip.

Fig. 9 is a sectional view on the line 9—9 of Fig. 6 showing the clearing lip merging with and in the plane of the peripheral rim, namely without any bias.

50 Fig. 10 is a sectional view on the line 10—10

of Fig. 6 depicting the clearing lip with a decreased bias.

Fig. 11 is a sectional view on the line 11-11 of Fig. 6 particularly illustrating the progressive bias or divergence of the tapered clearing lip.

Fig. 12 is an enlarged sectional view taken on the line 12-12 of Fig. 6 illustrating the fading tapered portion of the wedge means adapted to tension an adjacent bent down prong of the strap.

Fig. 13 is an enlarged transverse sectional view on the line 13-13 of Fig. 7.

Fig. 14 is a view of the strap with its companion bent down prongs against the top most sheet of the stack of papers.

Fig. 15 is a plan view of the compressor according to Figs. 1-13 threaded laterally on one of the bent down prongs, and

Fig. 16 is a plan view of the compressor telescoped on one of the bent down prongs and adapted to be swiveled thereon in a direction towards the other prong to removably interlock therewith.

The file fastener is generally denoted F and includes a strap comprising a base plate or member 10 provided with flexible and foldable companion prongs 11 and 12 integral with the base member 10. The stack of papers S includes aligned perforations 13 for the reception of the companion prongs 11 and 12 permitting the stack to be arranged on the base plate 10. The base plate and prongs characterize a one piece strap of a suitable sheet metal material although other types of material may be utilized.

The file fastener F is also characterized by a compressor or compressor plate broadly denoted C and may be of sheet metal, cardboard, or of an appropriate plastic material. This compressor plate is a one piece member having a length less than the distance between the companion prongs 11 and 12 when the latter are substantially normal to the base or base plate 10 and has a width several times that of the width of the prongs. Hence the terminals 14 of the companion prongs when bent down against the stack may be desirably covered and disengageably locked by raised boss or rib 15 extending longitudinally of the compressor plate. This boss terminates at the gap 16 and the slot 17.

By the present arrangement the struck out rib 15 may be said to be encompassed by a peripheral rim generally denoted R, comprising four marginal portions or flanges, namely, a lower marginal portion 18 merging with the side or end marginal portions 19 and 20 and the upper marginal portion or lip 21, the side marginal portions 19 and 20 together with the lower marginal portion 18 being interrupted by the struck out strengthening bead or rib B including the longitudinal portion 22 running lengthwise of the lower marginal portion and including the leg portions 23 and 24 disposed widthwise along the side marginal portions 19 and 20.

As a commentary with respect to the rim R, it is apparent that slot 17 starts at the juncture of the lower marginal portion 18 and side marginal portion 20 and extends uninterruptedly to the upper edge 26 of the upper marginal portion or lip 21, the gap 16 however, is merely between the lower and upper marginal portions 18 and 21 and between the side marginal portions 19 and the boss 15. Since the side marginal portion 20 is spaced from the upper marginal portion 21 it may be said to characterize a clearing wing W having a curved corner 27,

The rim R about the rectangular boss 15 except for rib or bead B and the outer marginal portion or lip 21 is in one plane, the lip or flange 21 however is progressively biased or bent outwardly from the plane of the compressor plate having its greatest taper or bias at corner 28 (Figs. 3 and 11) and gradually diminishes to be in the plane of the compressor plate (Figs. 9 and 11).

The rib portions 23 and 24 have tapered or fading off terminals 29 and the corners 30, 31 and 32 of the compressor are likewise rounded as shown while the base or plate 10 includes longitudinally arranged reinforcing ribs 34,

As an important commentary it should be observed that the elevation of the ribs 23 and 24 are of a height substantially equal the height of boss 15 and these ribs characterize wedge means for tensioning the bent down prong for drawing the base 10 towards the compressor in locking the compressor onto the prongs.

In Figs. 1 and 2 the prongs 11 and 12 are substantially at right angles to the base 10 of the strap and threaded through the perforations 13 to arrange the bottom of the stack on the base 10. Thereafter prong 11 is threaded through gap 16 permitting the terminal 14 to be received or telescoped in the keyway or channel 35 defined by the boss 15. The end face 36' then drops to be positioned on the uppermost or top sheet of the stack and is interlocked although not necessarily with boss 15. Subsequently the compressor is swiveled in the direction indicated by the arrow in Fig. 2. By this action, the terminal 14 of this prong is bent down but over the rib portion 23 (Fig. 3). Thereafter the compressor is swiveled slightly towards the operator or clockwise to arrange the wing 27 clear of the prong 12. Thereafter this prong is bent down against the stack (Fig. 4). The lip or free marginal flange 21 is now ready to be automatically slipped over the bent down prong 12 and particularly the terminal 14 thereof. This is accomplished by rotating the compressor counterclockwise as indicated by the arrow in Fig. 5. It follows that wing W goes under the bent down terminal 14 of the prong 12 while the biased flange 21 rides over this terminal 14 which now enters slot 17 (Fig. 5). Further counterclockwise rotation of compressor causes the lip 21 to shift over and beyond terminal 14 of prong 12 and ultimately boss 15 straddles and interlocks with terminals 14 of the companion prongs 11 and 12 (Fig. 6).

The tapered portion 29 of the bead or rib 24 allows the latter to be readily received under the bent down prong 12 while the body of the ribs 23 and 24 upon the rotation of the compressor to its interlocked relation with the bent down terminals 14 of the prongs 11 and 12 act as wedge or cam means to desirably tension the bent down prongs providing therein the concavo convex portions 35 and 36 (Fig. 7). By this action the base is urged tightly against the bottom of the stack while the end or side marginal portions 19 and 20 are urged tightly towards the top of the stack, the terminals 14 binding frictionally against the inside horizontal face of the keyway or channel 35. It follows that the compressor is tightly and securely held against the stack and of course interlocked with the bent down prongs.

Rotation of the compressor may be facilitated if desired by a raised finger piece portion 37 struck out of the rib portion 22 and to unlock the compressor the operator grasps the biased lip 21 and lifts the latter slightly. This causes the boss 15 to clear the bent down terminals

14 and hence the compressor is swiveled by the coaction of end face 36' against the prong 11 which serves as fulcrum means.

With the boss disengaged from the terminals 14 and compressor pivoted or swiveled clockwise, slot 17 withdraws from the bent down terminal 14 of prong 12 and thereafter the compressor is withdrawn from prong 11.

As an alternative mode of initially telescoping the compressor with one of the prongs, terminals 14 of the companion prongs may be bent down against the stack (Fig. 14). Subsequently the compressor is threaded on terminal 11 and slidably shifted laterally towards this prong (Fig. 15), thus removably telescoping therewith. Thereafter the compressor is swiveled or rotated clockwise relative to prong 11 taking the position shown in Fig. 16, after which the compressor is rotated on the bent down prong 11 and swiveled or pivoted counterclockwise as indicated by the arrow (Fig. 16). By this action wing W goes under the prong 12 and the biased lip 21 rides over this prong and ultimately boss 15 disengagably interlocks with the prongs which are tensioned by the beads 23 and 24 as in the case of Figs. 5 and 6, otherwise in structure and operation the compressor of Figs. 15 and 16 is identical to the compressor illustrated in Figs. 5 and 6.

In Fig. 5 terminal 14 is shown interlocked with the hollow boss 15. In such case the compressor if manually actuated shifts terminal 14 of prong 11 bodily therewith as illustrated and out of alignment with terminal 14 of prong 12. However it is not necessary to disturb the alignment of terminal 14 since the compressor may be raised to lift the boss 15 from terminal 14 of prong 11 and thereafter the compressor may be rotated on the terminal 14 of prong 11 as in the manner shown in Fig. 16. At any rate when the compressor is interlocked with both of the bent down prongs, the wedge means 23 and 24 has deformed the terminals 14 adjacent the juncture of their bends with their respective bodies of the prongs.

While the invention has been described in detail and reference has been made to a specific application thereof, it is to be understood that the invention herein disclosed is not limited to such specific application and it is intended that all matter contained in the above description or shown in the accompanying drawings shall be interpreted as illustrative and not in a limiting sense without departing from the invention or sacrificing the advantages thereof.

I claim:

1. A compressor for a file fastener wherein the bottom of a stack is seated on the base of a strap and a pair of spaced flexible and foldable prongs of the strap are adapted to be projected through spaced openings in the stack, said compressor embodying a relatively elongated plate of a length less than the distance between said prongs when the latter is disposed substantially normal to said stack and of a width greater than the width of said prongs, said plate having a longitudinally arranged hollow boss, a rim peripherally encompassing said boss and comprising a side marginal portion, a wing portion and upper and lower marginal portions, said upper portion characterizing a lip integral with said side marginal portion and disposed on a bias relative to and substantially coextensive with the length of said boss and having an outer free edge, wedge means projecting from said side marginal portion and from said wing portion, said plate hav-

ing a slot extending from said edge to said lower marginal portion, said plate having a gap encompassed by said side marginal and lower portions, said boss and lip, said gap adapted to receive one of said prongs for removable reception of the latter by said boss for folding said last mentioned prong downwardly towards said stack upon downward swingable displacement of said plate towards said stack, said slot adapted to receive the other prong of said pair subsequent for bending of said last mentioned prong towards said stack whereupon said plate may be bodily shifted whereby said wing portion shifts under and said lip shifts over said last mentioned prong to straddle the latter to dispose said boss in removable interlocking engagement with said prongs, said wedge means characterizing cam means for tensioning said prongs for urging said base and plate towards said stack, and said lip adapted to be lifted away from said stack to unlock said boss from said prongs.

2. A compressor for a file fastener wherein the bottom of a stack is seated on the base of a strap and a pair of spaced flexible and foldable prongs of the strap are adapted to be projected through spaced openings in the stack, said compressor embodying a relatively elongated plate of a length less than the distance between said prongs when the latter is disposed substantially normal to said stack and of a width greater than the width of said prongs, said plate having a longitudinally arranged hollow boss, a rim peripherally encompassing said boss and comprising a side marginal portion, a wing portion and upper and lower marginal portions, said upper portion characterizing a relatively elongated lip disposed longitudinally of said plate and substantially coextensive with the length of said boss and integral with said side marginal portion and progressively sloping upwardly and away from said side marginal portion and having an outer free edge, wedge means projecting from said side marginal portion and from said wing portion, said plate having a slot extending from said edge to said lower marginal portion, said plate having a gap encompassed by said side marginal and lower portions, said boss and lip, said gap adapted to receive one of said prongs for removable reception of the latter by said boss for folding said last mentioned prong downwardly towards said stack upon downward swingable displacement of said plate towards said stack, said slot adapted to receive the other prong of said pair subsequent for bending of said last mentioned prong towards said stack whereupon said plate may be bodily shifted whereby said wing portion shifts under and said lip shifts over said last mentioned prong to straddle the latter to dispose said boss in removable interlocking engagement with said prongs, said wedge means characterizing cam means for tensioning said prongs for urging said base and plate towards said stack, and said lip adapted to be lifted away from said stack to unlock said boss from said prongs.

3. A one piece compressor, for a file fastener with a pair of spaced and flexible prongs extending from a base on which a stack is mounted and wherein said prongs are adapted to be bent against said stack, comprising; a relatively elongated plate having a hollow boss for removably interlocking with said prongs, a peripheral rim encompassing said boss and including a side marginal portion, a lower marginal portion, a wing and an upper tapered lip integral with said side marginal portion and substantially coextensive

with the length of said boss, and having a free edge sloping upwardly away from said side marginal portion, said plate having a slot extending from said edge to said lower marginal portion and arranged between said lip and wing and said boss and wing; said plate having a gap encompassed by said lip, side and lower marginal portions, and said boss; wedge means projecting from said side marginal portion and said wing and extending widthwise of said plate; said compressor adapted to be moved relative to said prongs of said pair whereby one of said prongs is removably received in said gap to permit rotation of said compressor relative to said last mentioned prong; said compressor adapted to be rotated towards the other prong of said pair to thread said last mentioned prong into said slot whereby said lip shifts over and said wing shifts under said last mentioned prong prior to interlocking of said boss with said

5 prongs, said wedge means deforming said prongs to urge said boss and compressor towards each other and tightly against said stack, and reinforcing means disposed longitudinally of said lower marginal portion and including an offset finger manipulating portion.
